METHOD AND APPARATUS FOR FORMING
METAL CLOSURES

John J. Williams, Wheeling, W. Va., assignor
to Hazel-Atlas Glass Company, Wheeling,
W. Va., a corporation of West Virginia

Application May 19, 1933, Serial No. 671,908

18 Claims. (Cl. 153—48)

The invention relates to a method and apparatus for forming metal closures, particularly metal closures provided with an incurved bead and lugs which are hidden or substantially hidden from view. The article produced by the present invention is not claimed in the present application. A particular cap or closure, produced by the present invention, is disclosed for the purpose of making the invention clear; but such cap is not claimed in this application, and as will appear hereinafter the method and apparatus of the present invention are capable of producing different caps.

One of the objects of the invention is to provide a method and apparatus by which, in a single pressing operation, an ordinary cylindrical blank is converted into a completed cap with an incurved bead and locking lugs.

Another object of the invention is to provide a method and apparatus by which parts of the blank will be positively curled inwardly, while other parts of the blank will merely be drawn inwardly, and to a lesser degree, by the positive inward curling of the other parts.

Another object of the invention is to provide a method of forming lug caps by which the production is greatly facilitated, with a consequent lower cost; and to provide an inexpensive and very simple apparatus by which the method can be carried out.

Various other objects and advantages of the invention will be apparent to those skilled in the art of manufacturing metal caps, from the following detailed description when taken in connection with the accompanying drawings; in which,

Figure 1 is a vertical sectional view of the mechanism, showing the conventional blank in place ready to be acted upon by the die; the parts being in raised position above the blank, and the section of the curling ring being taken through the portions where the lugs are formed.

Figure 2 is a view similar to Figure 1, but with the parts having been moved down to cap forming position.

Figure 3 is a view similar to Figure 2, but with the section of the curling ring being taken through the portions which form the incurled bead.

Figure 4 is a perspective view of the curling ring removed from the apparatus.

Figure 5 is a diagrammatic view illustrating the formation of the incurled bead and lugs.

Figures 6, 7 and 8 are enlarged fragmentary sectional views through a cap in the process of

being formed, and illustrating some of the steps in the formation thereof; and

Figure 9 is a perspective view of a completed cap.

The preferred apparatus will now be described in detail, but it is to be understood that the present invention is in no manner limited to the specific apparatus shown and described. Numeral 1 refers to an ordinary cylindrical shaped blank, formed in the usual manner and placed, 5 by any desired means, upon the plug 2. A resiliently mounted centering plate (not shown) is preferably associated with the plug. This plug is mounted on the die block 3 which is secured to the bolster plate of an ordinary punch press 10 (not shown), or to any other desired machine.

Numeral 4 refers to the ring holder, which is clamped to the ram of an ordinary punch press (not shown), or to any other mechanism providing a reciprocable movement. This reciprocable ring holder carries several parts, which will now be described. Numeral 5 indicates a guide or centering ring, which is carried by the holder, and which has a snug fit with the cap blank; the lower end of this ring being preferably flared, 25 as indicated by numeral 6. The curling ring or die is referred to by numeral 7, and it is provided with an annular curling groove 8, which is semi-circular in cross-section. This curling groove is continuous except at the points where the lugs 30 are to be formed, and at these points the die is provided with cut-out portions 9. The functions of the curling groove and the lug-forming cut-out portions will be described hereinafter. Numeral 10 refers to a clamping and ejector pad, 35 provided with an upwardly extending stem 11. Arranged about the upper end of the stem is a coil spring 12; the lower end of the spring being seated in the upper end of the holder, and the upper end of the spring resting against a washer 13 secured in place by a cotter pin 14 or by other suitable means. Within the holder there is arranged about the stem 11 a heavy coil spring 15; the upper end of the spring resting against the holder and the lower end thereof resting 40 against a washer 16.

The invention will be better understood by first describing the operation of the parts without describing the particular effects produced on the cap blank, and then describing the manner in 50 which the die forms the incurled bead and the lugs on the blank in a single operation.

As the ram of the press descends the guide or centering ring 5 fits snugly around the cap blank 1, thereby not only accurately centering the blank 55

with respect to the descending die ring, but also supporting the skirt or flange of the blank to prevent any outward bulging of the skirt when the die acts on the rim or edge of the blank. Further 5 downward movement forces the pad 10 firmly against the inside top of the blank thereby holding the blank firmly seated on the plug 2 during the pressing operation. The pad 10 now remains stationary, but the curling ring or die 7 continues 10 to descend against the pressure of spring 15, to the desired position to produce the desired effect on the cap blank; the parts in their lowered or cap-forming position being shown in Figures 2 and 3. The ram now rises, and during the first 15 part of the upward movement the pad 10 is held stationary against the cap by the spring 15. The cap is thus moved from the die but it may still be within the centering ring 5 by reason of the snug fit between this ring and the cap. As the upward 20 movement of the holder and ram continues the die ring 7 and washer 16 come together and then the pad rises with the holder, and during the continued upward movement the stem 11 of the pad 10 strikes a stop (not shown) on the press. 25 This causes the upward motion of the pad to be stopped, while the other parts of the upper die, including the centering ring 5, continue to rise, the spring 12 being compressed. This action causes the cap to be ejected from the centering 30 ring, and it then falls into a container (not shown). The parts are now ready to start another cycle of operation.

Having described the purely mechanical operation of the parts, I shall now describe in some 35 detail the effects produced upon the cap blank by the descending die, and the method by which the inturned curl and the lugs are formed in a single pressing operation.

When the die first comes into contact with the 40 rim or edge of the cylindrical blank, the curling groove 8, which is a complete circle, and which is substantially semicircular in cross-section except where the lugs are formed, causes the entire rim or edge of the blank to start to curl inwardly, as indicated by numeral 17 on the diagrammatic 45 Figure 5. The lug forming portions 9 of the die are of peculiar construction. The outer part is curved on the same curvature as that of the curling groove and conforms exactly therewith, as clearly shown in Figure 4; but it will be noted that the curvature of the curling groove is completed to a semicircular form, while the lug-forming portions curve in only a very slight distance, preferably just enough to start the metal 50 to curve. Of course the extent of the curved portion may be varied as desired. The tops of the cut-out portions extend inwardly and upwardly from the point where the curved surface ends, in the specific form illustrated herein; but 55 it will be understood that this inclined portion may be entirely omitted, as it has no effect on the operation. In other words, the die could be cut away completely at the points where the curvature ends, so that there would be an open space 60 over the metal where the lugs are being formed, except for the slight curved portion.

As the die continues to descend, the curling groove, which is substantially semicircular in 65 cross-section, positively causes the metal of the blank to continue its curving until it makes a complete or substantially complete circle, as shown by dotted lines in the diagrammatic Figure 5, and referred to by numeral 19. However, the metal of the blank at the cut-out portions of the die, is not positively forced to continue its

curving; but on the contrary, these cut-out portions permit the metal which is being curled to merely draw the metal at the cut-outs downward. So that the metal at the cut-outs lags behind the other metal and will first assume a substantially horizontal position, and if the die descends further the metal will assume a downwardly inclined position, as indicated by dotted lines in Figure 5 and referred to by numeral 20. Further descent of the die will draw the lugs 10 down still farther, but the position indicated by numeral 20 is approximately the usual position I prefer the lugs to assume. Of course Figure 5 does not illustrate the actual shape the metal takes in forming the lugs by the single pressing 15 operation, as it is intended merely to illustrate diagrammatically how the rim of the blank is forced to form an inside curl while the cut-outs permit metal at those points to lag behind and be drawn down by the curled portions, as distinguished 20 from being positively forced to a particular position. The exact structure of the lugs thus formed, will be better understood by reference to Figures 6, 7, 8 and 9. Figures 6, 7 and 8 show some of the steps in the formation of a lug, 25 and Figure 9 shows a completed cap. Figure 6 shows the conventional plain cylindrical cap blank before the die has been brought into contact with it. In Figure 7 the cap is in process of formation, and it will be noted that the bead has 30 already curled up into a substantially semicircular form, as indicated by numeral 21, while the lug forming portion 22 is lagging behind. It will also be noted that the lug forming portion is connected to the partly curled bead by somewhat 35 triangular-shaped portions 23. In Figure 8 the die has descended far enough to complete the specific form of cap shown in Figure 9. By reference to Figure 8 it will be noted that the curled portion 21 has been forced to a position substantially completing a circle, while the lug-forming portion 22 while still lagging behind yet has been drawn to a position where it inclines slightly upward toward the top of the cap. The lug and incurled bead are connected by the triangular 40 portions or gussets 23. The present invention is not limited to the making of any specific cap, and the cap as an article is not claimed in the present application. Nevertheless it will be helpful 45 in understanding the present invention, to describe certain other effects which are produced upon the blank by the single pressing operation in completing a specific form of cap which is 50 shown in Figure 9.

While the incurled bead is being formed and while the lug-forming portions are being drawn inwardly and downwardly by the incurling of the bead, an arch or depression is formed in the bead where the lugs are located, as indicated by numeral 24, Figure 9. These arches or depressions terminate in slight humps 25, which rise a very slight distance above the normal plane of the bead. It is to be noted that these arches are not flat transversely but are curved transversely, as shown in Figure 8. In this figure, the section is taken at the center of the arch, and one of the slight humps 25 is shown in elevation. As the cap per se is not claimed here, it need not be further described; it being sufficient to state that this arch is formed by the method and apparatus herein disclosed, and that the cap thus produced, with a lug having a portion which is arched in one direction and the arched portion being curved transversely, provides an unusually strong lug formation. If the die is caused to descend 55

still further, thereby causing the lugs to be more sharply inclined upwardly to an almost vertical position, the arches and humps will be drawn out of the lug formation, thereby producing a cap 5 having its rim smooth and curved throughout, when viewed from the exterior.

While the invention has been described in great detail, yet it is to be clearly understood that the present invention is not in any respect limited 10 to details shown and described, but relates broadly to a method and apparatus for forming metal caps in which the bead is positively curled inwardly and the lugs lag behind and are drawn inwardly by the incurled portion, and the cap being 15 completed from a conventional cylindrical blank by a single pressing operation.

Having fully described my invention, what I claim is:

1. The method of forming a metal cap from a 20 cup-shaped blank in a single stroke of a die which comprises curling an inside bead on the skirt by the pressure of a die, and by the same stroke of the die causing the inwardly curling bead to draw inwardly adjacent portions of the skirt to form 25 lugs.

2. The method of forming a metal cap from a cup-shaped blank in a single stroke of a die which comprises curling inwardly certain portions of the skirt by the pressure of a die and by these 30 curling in portions dragging inwardly lagging portions under the same die stroke, to form lugs.

3. The method of forming a metal cap from a cup-shaped blank which comprises the forming of inwardly extending lugs at intervals by curling 35 inwardly other portions of the blank skirt, in a single stroke of a die.

4. The method of forming a metal cap from a cup-shaped blank which comprises the forming of inwardly extending lugs at intervals without 40 the direct application of pressure thereto by directly applying pressure to other portions of the blank skirt to form an incurled bead, in a single stroke of a die.

5. The method of forming a metal cap which 45 comprises engaging a die with the raw edge of the skirt of a cup-shaped blank and causing said edge to be curled inwardly, and then further curling portions of the skirt to cause the raw edge of other portions to be dragged inwardly to form 50 lugs.

6. The method of forming a metal cap which solely comprises curling inwardly the skirt of a cup-shaped blank and by this inward curling causing the raw edge of certain portions of the 55 skirt to be dragged inwardly to form lugs.

7. The method of forming a metal cap which comprises engaging a die with the raw edge of the skirt of a cup-shaped blank and curling inwardly portions of the skirt, forming lugs which 60 project inwardly of the inwardly curled portions, and forming depressions in the edge of the cap adjacent the lugs.

8. The method of forming a metal cap which 65 comprises engaging a die with the raw edge of the skirt of a cup-shaped blank and curling inwardly portions of the skirt, forming lugs which project inwardly of the inwardly curled portions, and forming humps with a depression therebetween in the edge of the cap adjacent the lugs.

9. The method of forming a metal cap which comprises engaging a die with the raw edge of the skirt of a cup-shaped blank and curling inwardly certain portions of the skirt, by this inward curling causing other portions of the skirt to be dragged inwardly to form lugs, and forming 5 depressions in the edge of the cap adjacent the lugs.

10. The method of forming a metal cap which comprises engaging a die with the raw edge of the skirt of a cup-shaped blank and curling inwardly certain portions of the skirt, by this inward curling causing other portions of the skirt to be dragged inwardly to form lugs, and forming humps with a depression therebetween in the 15 edge of the cap adjacent the lugs.

11. An apparatus for forming metal caps including a die having means for engaging and inwardly curling the raw edge of the skirt of a cup-shaped blank, and means on said die causing portions of the skirt to be drawn inwardly, from positions within the boundary of the skirt, by the inward curling bead to form lugs. 20

12. An apparatus for forming metal caps including a die having an annular groove to curl 25 inwardly the edge of a cup-shaped blank to form an incurled bead, said annular groove having cut-out portions at intervals in its inner wall only to permit portions of the blank to be drawn inwardly to form lugs. 30

13. An apparatus for forming metal caps including a die having an annular groove of substantially semicircular cross-section to curl 35 inwardly the edge of a cup-shaped blank to form an incurled bead, said semicircular groove having a continuous wall, and having its inner wall cut away at intervals, to permit portions of the blank to be drawn inwardly to form lugs.

14. An apparatus for forming metal caps including a die having means for exerting direct 40 pressure against portions of the raw edge of a cup-shaped blank to inwardly curl the edge of the blank, the die being cut away at other portions, thereby permitting the raw edge of the blank at these points to be freely drawn inwardly 45 to form lugs, the angle the lugs assume with respect to the skirt of the cap varying in accordance with the extent of the curvature of the bead.

15. An apparatus for forming metal caps, comprising a single die, means on said die for curling 50 inwardly the raw edge of a cup-shaped blank, and other means on the die for causing portions of the blank to be dragged inwardly, to form lugs.

16. An apparatus for forming metal caps, comprising a single die, means on said die for forming 55 an incurled bead on a cup-shaped blank, and means for causing portions of the raw edge of the blank to be dragged inwardly, to form lugs.

17. An apparatus for forming metal caps including means for forming an incurled bead on 60 a cup-shaped blank, and means for causing portions of the raw edge of the blank to be dragged inwardly, to form lugs.

18. The method of forming a metal cap which comprises exerting curling pressure on the raw 65 edge of the skirt of a cup-shaped blank to give only a slight inward curl throughout the edge, and after this slight curling relieving the curling pressure at certain points only, to form lugs.

JOHN J. WILLIAMS. 70
